INVENTOR,
Michael Landi,
BY
John Edward
ATTORNEY.

UNITED STATES PATENT OFFICE.

MICHAEL LANDI, OF PATERSON, NEW JERSEY, ASSIGNOR, BY DIRECT AND MESNE ASSIGNMENTS, OF ONE-THIRD TO ALFRED LANDI AND ONE-THIRD TO ALFONSO ABATE, BOTH OF PATERSON, NEW JERSEY.

PICKER CHECK FOR LOOMS.

Application filed May 15, 1923. Serial No. 639,051.

To all whom it may concern:

Be it known that I, MICHAEL LANDI, a subject of the King of Italy, residing at Pater-
son, in the county of Passaic and State of
New Jersey, have invented certain new and
useful Improvements in Picker Checks for
Looms, of which the following is a specifica-
tion.

In box looms the picker for the shuttle
10 usually slides on a rod at the back of the
framing in which the boxes are guided verti-
cally and which forms a part of the rocking
batten-including structure, and its inward
movement is at present yieldingly checked
15 by a buffer consisting of a leather strap
which is folded zig-zag fashion and has its
several folds penetrated by the rod. This
buffer is quite unsatisfactory for the purpose
in hand because it soon increases in pliability
20 upon being put into use and is also affected
by atmospheric conditions, so that at differ-
ent times it offers widely varying degrees of
resistance, which results in the blow of the
picker being irregular in force and produces
25 consequent irregularities in the woven goods.

The object of this invention is to provide
an attachment for box looms for yieldingly
30 checking the picking motion of the picking
medium which shall oppose a substantially
constant degree of resistance practically per-
manently and shall be simple in construction,
readily attachable to any box loom, of en-
35 during character, and capable of ready ad-
justment as circumstances may require.

In the drawing,

Fig. 1 shows the right-hand end portion
40 of a loom in rear elevation and with my
picker checking means attached thereto;

Fig. 2 is an outside elevation on a larger
45 scale of said means and the picker stick; and
Fig. 3 is a front elevation of said means.

In the loom frame *a* is arranged to rock
back and forth the usual structure including
the batten *b* and the lay swords, only one of
45 which is shown at *c*, *d* representing the shaft,
journaled in the frame, carrying the lay
swords; said structure also includes the
framing *e* in which the shuttle boxes *f* slide,
g being the rod which carries the boxes and
50 forms a part of the means for reciprocating
them vertically. *h* is the picker stick ful-
crumed in a bracket *i* projecting from the
shaft *d*; it is normally held in the full line

position shown in Fig. 1 by the spring *j*, be-
ing adapted to have its picking strokes im-
parted thereto by well known means includ-
ing the strap *k*. The upper end of the picker
stick extends between the back of the fram-
ing and a horizontal rod *l* which is secured
to the framing in parallel relation thereto,
m being the picker which slides on the rod
and in the usual way has an opening through
which the picker stick extends.

Bolted to the under side of the framing
c near the lay swords *c* is a bracket *n* which
projects rearwardly clear of the framing.
This bracket has an arm *o* which projects
downwardly and outwardly from the lay
sword at an incline, having at its free end a
forwardly projecting boss *p* from which in
turn projects a horizontal stud or pivot *p*
which may be equipped with a cotter-pin *q*.
Carried by the arm is a stop which consists
of an elongated plate *r* arranged approxi-
mately horizontally and having its outer end
s bent forward to form the stop proper. The
stop *r* is secured to the front face of the arm
by a bolt *t* having a clamping nut *u*, the bolt
penetrating a horizontal slot *v* in the stop, so
that the latter may be adjusted horizontally.
The bracket *n* has upstanding therefrom at
about the same point from which the arm
projects downwardly and outwardly an in-
tegral stop *w* which is bent outwardly and
preferably has its free end face arranged at
a downward and outward incline and
equipped with an elastic buffer *x*.

Pivoted on the stud *p*, between the boss
and the cotter pin, is a lever *y* upstanding
from the pivot and having a forwardly
projecting arm or lug *z* which preferably
presents a rounded outer surface *z'*. This
lever is movable on the pivot from engage-
ment with the stop proper *s* to engagement
with the buffer *x*, being sufficiently below
the rod *l* so as to clear the same when it
swings from one limit of its movement to
the other; its projection *z* lies in the plane
of movement of the picker stick *h*. The
bracket *n* and the lever *y* have hooks *n'* and
y' and these are connected by a spiral spring
z, which normally acts to hold the arm bear-
ing against the stop proper *s*.

When the device is in use, each time the
picking means *h m* is impelled inwardly or
made to perform the picking stroke the

picker stick h impinges against the rounded face z' of the projection z of lever y , the shock being taken up by the spring z , which yieldingly resists the inward movement of the lever. The inward movement of the lever is finally definitely limited by the elastic buffer w , the return movement of the picking means is assisted by the spring means 2 as the latter contracts upon the inward movement of the lever y being checked.

10 An important feature of my invention is the outward inclination of the arm o of the bracket which, at the same time that it brings the pivot for the lever y well outward to permit an ample swing of the lever for the purpose in hand, permits the arm and consequently the bracket as a whole to be light in construction and yet strong enough to resist breakage.

15 20 Another important feature of my invention is the stop r which upon adjustment horizontally varies the extent of throw of the lever to the end that the point of impact of the picking means therewith may be set outward or inward in the path of travel of said means.

Having thus fully described my invention, what I claim as new and desire to secure by Letters Patent is:—

25 In combination, with the batten-including structure of a loom, a picking means movable therein inwardly and outwardly, a bracket secured to said structure near the inward limit of motion of said means and having an arm inclined downwardly and outwardly and a stop near the upper end of the arm, a lever fulcrumed in the arm to move in a plane parallel with the path of movement of said means against said stop and projecting upwardly from its fulcrum into the path of said means, said bracket having near the lower end of the arm another stop against which the lever is adapted to bear at an outward incline and from which the lever is movable inwardly, and a 30 spring extending parallel and connected with the arm at the upper end thereof and with the lever near the lower end of the arm and normally holding the lever against the stop.

35 In testimony whereof I affix my signature.

40 MICHAEL LANDI.
